John H. Keiper Inventor

Castro & Co.

UNITED STATES PATENT OFFICE.

JOHN F. KEIPER, OF EVERETT, WASHINGTON.

ORE-ROASTING FURNACE.

SPECIFICATION forming part of Letters Patent No. 630,510, dated August 8, 1899.

Application filed April 23, 1898. Serial No. 678,637. (No model.)

To all whom it may concern:

Be it known that I, JOHN F. KEIPER, a citizen of the United States, residing at Everett, in the county of Snohomish and State of Washington, have invented a new and useful Ore-Roasting Furnace, of which the following is a specification.

My invention relates to ore roasting and calcining furnaces designed particularly for use in the treatment of sulfurous and arsenical ores; and the object in view is to provide means for accomplishing a uniform heating or roasting of the ore and more uniform distribution thereof over the surface of the hearth and greater facility in depositing the ore upon the hearth and in discharging the same therefrom when sufficiently roasted.

Further objects and advantages of this invention will appear in the following description, and the novel features thereof will be particularly pointed out in the appended claims.

In the drawings, Figure 1 is a central vertical section of a furnace constructed in accordance with my invention, such a section being taken longitudinally of the hopper. Fig. 2 is a plan view of the furnace with the domed top omitted. Fig. 3 is a transverse section of the hopper and an elevation of the contiguous portion of the furnace to show the means for securing the rabble-shaft in its adjusted positions. Fig. 4 is a detail sectional view of the hearth, taken transversely to one of the radial discharge-openings and through the adjacent receiving-trough and the rabble. Fig. 5 is a detail view in perspective of a portion of the rabble to show the stirring and discharging blades thereof.

Similar numerals of reference indicate corresponding parts in all the figures of the drawings.

My invention relates to that class of ore-roasting furnaces wherein the ore is deposited upon a circular or annular hearth, and that embodiment of my invention which I deem best adapted to carry out the objects in view includes an annular furnace-wall 1, having a domed top or cover 2, provided with a radial series of ore-inlet openings 3, with which communicates a feed-hopper 4, each of said ore-inlet openings having a controlling slide or valve 5, whereby any desired number of open-

ings located at different distances from the center of the furnace may be opened to vary the rapidity with which ore is admitted to the 55 furnace and also to control the points at which the ore is admitted.

Coextensive with the furnace and mounted for revoluble movement therein is a circular hearth 6, which in the construction illustrated is provided with a refractory ore-receiving surface 7, of brick or analogous material, supported by a metal base-plate 8, which in turn is upheld by frame-bars consisting of I-rails 9. These rails are preferably disposed radially, and at suitable points a plurality of the rails, as shown at 9^a, may be disposed parallel with each other throughout, and the refractory surface 7 and plate 8 may be slotted to form radially-elongated ore-discharge openings 10. Refractory facings 11 are preferably fitted in the inner sides of the rails 9^a to prevent contact of the heated ore with the said rails, and each discharge-opening is also fitted with a closure, consisting in the construction illustrated of a slide 12, fitted between the lower flanges of the rails 9^a and the lower edges of the refractory facings 11.

The hearth, as above indicated, is constructed for rotary movement to bring different portions of its surface successively on a line connecting the fire-box or combustion-chamber 13 and the outlet-flue 14, said fire-box and outlet being preferably arranged at 85 diametrically opposite points and communicating with the interior of the furnace, and the means illustrated in the drawings for supporting the hearth include a central spindle 15, extending at its extremities respectively 90 above and below the plane of the hearth, with the lower extremity seated in a socket-bearing 16, supported by a pedestal, base, or foundation 17. Also attached to the under sides of the radial frame-bars 9 of the hearth 95 is a circular track-rail 18, which traverses a plurality of bearing-rolls 19, each suitably mounted upon a base 20. Various means may be provided for imparting continuous rotary motion to the hearth; but in the drawings I have deemed it sufficient to illustrate a cable 21 or its equivalent, such as a chain, traversing spaced brackets or sprockets 22, depending from the under side of the hearth

and adapted to be actuated by any suitable devices.

Mounted upon the upper end of the spindle 15 is a cap 23, an antifriction-bearing 24, consisting of balls or rollers, being interposed between the cap and the extremity of the spindle, and mounted at their inner ends in half-bearings 25 or their equivalents carried by said cap are rabble-spindles 26, preferably of tubular construction and extending radially of the hearth above the plane thereof and through suitable guides or apertures 27 in the side walls of the furnace. The outer ends of the rabble spindles or shafts are fitted with operating levers or handles 28, to which are connected quadrant-arms 29, extending through fixed guides 30 and combining with said guides to form means for securing the levers or handles 28 at the desired adjustment. In the construction illustrated the holding-arms 29 are provided with offsets or shoulders for engagement with the guides 30 when the levers or handles 28 are in a pendent position, as shown in full lines in Fig. 3, 25 said levers or handles being adapted to bear against the guides when they occupy the approximately horizontal positions indicated in dotted lines in Fig. 3; but it will be understood that any equivalent means for securing 30 the rabble-shafts at the desired adjustment may be adopted.

The rabble-shafts, of which any desired number may be employed, but which occupy fixed positions with relation to the furnace, 35 carry a series of rabble or stirring blades 31, disposed at an angle to the radius of the hearth, the blades of different rabble-shafts being inclined in different directions to cause a backward-and-forward or radial shifting of 40 the ore on the surface of the hearth, and distributing or discharge blades 32, which preferably extend continuously throughout the radius of the hearth, are adapted to be turned down into operative relation with the hearth 45 when it is desired to spread the ore evenly over the surface of the hearth or to discharge the ore after being sufficiently roasted through the discharge slots or openings 10, hereinbefore described. The normal position 50 of the rabble is that which it occupies when the rabble-blades 31 are located in operative relation with the hearth, as indicated in Fig. 2, when the operating lever or handle 28 is in a pendent or vertical position; but when it is desired to distribute or spread the ore upon 55 the surface of the hearth the rabble-shaft may be turned to an intermediate point to depress the blade 32. On the other hand, when it is desired to discharge the ore the 60 rabble should be turned to that position in which the discharge-blade 32 is perpendicular to the surface of the hearth or with the lever or handle 28 in the position indicated in dotted lines in Fig. 3, and also the slides by 65 which the discharge openings or slots 10 are controlled should be moved sufficiently to allow the ore which is backed up by the dis-

charge-blades 32 to escape through said openings.

The rabble shaft or spindle 26 is tubular in construction in order to provide for admitting thereto a cooling agent, such as water, and in order that a continuous flow of the cooling agent may be established during the operation of the mechanism to avoid the burning out of the metal forming the rabble I employ an inlet-pipe 33, extending through a loose or revolvable head 34 in the outer end of the rabble-shaft and terminating contiguous to the inner end of said shaft, and an overflow or discharge tube 35, communicating with the rabble-shaft near its outer end. The inlet and outlet or discharge tubes 33 and 35 are out of contact with the walls of the rabble-shaft. 85

At the center of the domed roof or cover of the furnace I have provided a working hole or twyer 36, fitted with a suitable removable cap or plug 37, and arranged at suitable points under the hearth and preferably contiguous to the vertical planes of the rabbles are receiving hoppers or troughs 38.

From the above description it will be seen that in operation the ore is continuously advanced and is successively moved to different parts of the interior of the furnace, whereby the contents of the furnace are uniformly heated, and this uniform heating of the ore is accomplished without the excessive strain upon the mechanism incident to the movement thereof by means of rotary rabbles. 95

Furthermore, it will be seen that when it is desired to discharge the contents of the furnace it is simply necessary to turn the rabble to bring its discharging-blade into operative 105 relation with the hearth and open one or more of the discharge-slots in the hearth, whereby as the latter rotates slowly but continuously the ore is backed into the slots and falls into the receiving trough or hopper. 110

Furthermore, it will be seen that any desired number of feed-openings, whereby ore is fed from the hopper 4 to the hearth, may be utilized in admitting ore in order to secure the desired rapidity of feed and the preferred 115 distribution of ore upon the surface of the hearth.

Various changes in the form, proportion, and the minor details of construction may be resorted to without departing from the spirit 120 or sacrificing any of the advantages of this invention.

Having described my invention, what I claim is—

1. An ore-roasting furnace having a rotary 125 hearth provided with a central spindle and annular supporting devices, and also provided with discharge-openings extending radially from the periphery approximately to the center of the hearth, valves for controlling said 130 discharge-openings and means for scraping the contents of the hearth into said discharge-openings, substantially as specified.

2. An ore-roasting furnace having a rotary

hearth, comprising radial frame-bars, a base-plate supported by the frame-bars, and a refractory surface supported by the base-plate, a central spindle fixed to said frame-bars and mounted in a suitable bearing, a stationary cap fitted upon the upper end of the spindle to allow independent rotation of the latter, a stirring device mounted at its inner end upon said cap, an annular track secured to the under sides of said frame-bars concentric with the spindle, and bearing-rollers traversed by said track, substantially as specified.

3. An ore-roasting furnace having a rotary hearth provided with an attached central upwardly-extending spindle, a cap loosely mounted upon said spindle to allow independent rotation of the latter, and provided with a bearing, and a rabble-shaft mounted at its inner end, to turn in said bearing, substantially as specified.

4. An ore-roasting furnace having a rotary hearth, a rabble located above the hearth and having interchangeable rabble-blades and a discharging-blade, and means for securing either of said blades in operative relation with the hearth, substantially as specified.

5. An ore-roasting furnace having a rotary hearth, a rabble located above the hearth and having a revolute blade-carrying spindle mounted in fixed bearings, arranged approximately parallel with the surface of the hearth and adapted to be turned to remove its blades from operative relation with the surface of the hearth, and means located exteriorly of the furnace for securing the spindle in its adjusted positions, to maintain the blades in the desired relation to the plane of the hearth, substantially as specified.

6. An ore-roasting furnace having a rotary hearth, a rabble located above the hearth and having a spindle carrying rabble-blades and a discharging-blade, and means for securing the spindle at the desired rotary adjustment, with either of said blades in operative relation with the hearth, substantially as specified.

7. An ore-roasting furnace having a rotary hearth, a rabble located above the hearth and having a revolute spindle arranged radially with relation to the hearth, rabble-blades on said spindle inclined to the radius of the hearth, and means for securing the rabble-spindle at the desired adjustment, substantially as specified.

8. An ore-roasting furnace having a rotary hearth, a rabble located above the hearth and having a revolute spindle arranged radially with relation thereto, rabble-blades on said spindle inclined to the radius of the hearth, a continuous discharging-blade on the spindle arranged in angular relation with the rabble-blades, and means for securing the rabble-spindle at the desired adjustment, substantially as specified.

9. An ore-roasting furnace having a rotary hearth provided with discharge-openings, a

rabble having a rotary spindle located above the hearth and carrying rabble-blades and discharging-blades disposed in angular relation, an exposed operating lever or handle attached to the rabble-spindle, and means for securing said lever or handle at the desired adjustment, substantially as specified.

10. An ore-roasting furnace having a rotary hearth provided with discharge-openings, a rabble having a rotary spindle located above the hearth and carrying rabble-blades and discharging-blades disposed in angular relation, an exposed operating lever or handle attached to the rabble-spindle, and means including a segment-bar attached to the lever or handle, and a fixed guide through which said segment-bar extends, the latter being provided with offsets for securing the lever or handle at the desired adjustment, substantially as specified.

11. An ore-roasting furnace having a rotary hearth, and means for agitating the contents thereof, a feed-hopper, and feed-openings communicating with the hopper and disposed in radial series above the hearth for discharging the contents of the feed-hopper upon the surface of the hearth, said feed-openings being each provided with independent controlling devices, substantially as specified.

12. An ore-roasting furnace having a rotary hearth, and means for agitating the contents thereof, a feed-hopper, and feed-openings communicating with the hopper and disposed in radial series above the hearth for discharging the contents of the feed-hopper upon the surface of the hearth, and independently-movable controlling-slides for feeding the openings, substantially as specified.

13. An ore-roasting furnace having a rotary hearth, in combination with a rabble having a tubular revolute spindle carrying rabble-blades, and extending at one end through the wall of the furnace, means for adjusting the spindle, a cap fitted in the end of the spindle, and inlet and discharge pipes extending through the cap and communicating with the interior of said spindle, for admitting and exhausting a cooling agent, substantially as specified.

14. An ore-roasting furnace having a revolute hearth provided with radial frame-bars including pairs of parallel I-beams, said hearth having a refractory surface provided with slots registering with the interval between said parallel beams, refractory facings, and slides supported by the flanges of said I-beams for controlling the discharge of ore through the slots, substantially as specified.

In testimony that I claim the foregoing as my own I have hereto affixed my signature in the presence of two witnesses.

JOHN F. KEIPER.
